- GB 177080 3/1922

Primary Examiner — Ricky Pham*(74) Attorney, Agent, or Firm* — McKee, Voorhees & Sease, PLC**CLAIM**

I claim the ornamental design for a perforated cone for cooking and serving appetizers, substantially as shown and described.

DESCRIPTION

FIG. 1 is a side elevation view of the perforated cooking and serving cone of the present invention; and,
FIG. 2 is a bottom perspective view of the cone.
The views not shown form no part of the claimed design.
